COMBINED MEDICINAL VAPORIZER AND
HOLDER THEREFOR OR THE LIKE

Walter L. Johnson, Evanston, and Donald B. Lowe, Jr.,
Batavia, Ill., assignors to Northern Electric Company,
Chicago, Ill., a corporation of Delaware

Filed June 23, 1960, Ser. No. 61,096

Term of patent 14 years

(Cl. D83—1)

Fig. 1

FIGURE 1 is a front elevational view of a combined medicinal vaporizer and holder therefor or the like, embodying our new design, a portion of the holder being shown in section;

The dominant features of our design reside in the full line portions of the drawings.

We claim:

The ornamental design for a combined medicinal vaporizer and holder therefor or the like, substantially as shown and described.
